CIRCUIT BREAKER

John G. Jackson, Detroit, Mich., assignor to
 Square D Company, Detroit, Mich., a corpora-
 tion of Michigan

Application August 15, 1935, Serial No. 36,247

45 Claims. (Cl. 200—116)

This invention relates to automatic electric circuit breakers and has for its object the provision of an improved multi-circuit circuit breaker.

Another object of this invention is to provide an economical automatic electric circuit breaker having a minimum of parts.

Another object of this invention is to provide a multi-circuit circuit breaker utilizing a common contact and a plurality of individual contacts for the individual circuits.

Another object of this invention is to provide a multi-circuit circuit breaker with a plurality of individual mechanisms, certain of whose contacts are at least electrically common.

Another object of this invention is to provide a multi-circuit circuit breaker with a main and a plurality of branch circuit breaker mechanisms, the load contact of the main and the line contacts of the branch circuits being common.

Another object of this invention is to provide an improved enclosure mounting for an electric circuit breaker.

Another object of the invention is the provision of a circuit breaker assemblage within a unitary sealable enclosure having electrically connected stationary contact surfaces with individual movable contacts cooperating therewith and with individual automatically and manually operable circuit breaker mechanisms for actuating the movable contacts.

Another object of the invention is the provision of an improved form of multi-circuit circuit breaker or circuit breaker assemblage providing certain electrically common parts and having structural mounting details characterized by the compactness and simplicity of the parts resulting in economy of manufacture without sacrificing the performance characteristics of the device.

Another object of the invention is an electric circuit breaker assemblage characterized by centrally disposed, electrically connected, contact surfaces with automatically and manually operable circuit breaker mechanisms at opposite sides of the contact surfaces and including movable contacts cooperating with the contact surfaces, the parts being mounted within an enclosure having electrical insulating and arc confining elements and common arc gas venting portions.

Another object of the invention lies in the provision of simplified and economical means for forming an enclosure for a circuit breaker assemblage so as to substantially prevent access

to the interior of the enclosure and to provide arc isolating and venting portions.

Other objects and features of this invention will be readily apparent to those skilled in the art from the following specification and appended drawings illustrating certain preferred embodiments of the invention in which:

Figure 1 is a front elevational view of the breaker according to the present invention with parts of the cover broken away to show the breaker interior.

Figure 2 is a vertical sectional view taken on the line II—II of Figure 1.

Figure 3 is a vertical sectional view of a single breaker mechanism showing the operating parts in over-load tripped position.

Figure 4 is a vertical sectional view of the single breaker mechanism showing the parts in reset position before the contacts are closed.

Figure 5 is a horizontal sectional view on line V—V of Figure 1.

Figure 6 is a fragmentary sectional view similar to Figure 5 showing a slightly modified construction.

Figure 7 is a detailed view of a magnetic arc suppressor plate.

The circuit breaker according to the present invention comprises an outside enclosing box 1 having a cover 2 hingedly mounted thereon. Within this box is disposed a sealable multi-circuit circuit breaker comprised of an insulating base 3 and a metal cover 4. The cover 4 is adapted to be sealably attached to the base 3 by means of rivets 5. The cover 4 extends across the width of the box and to one side there is riveted or otherwise attached a hinge 6 which is bolted to the side walls of the box as at 7. The opposite side of the metal cover 4 is provided with a flange 8 carrying a bolt 9 adapted to be received within a slot 11 in the box wall to secure the cover 4 and breaker mechanisms within the box 1. The cover 4 is provided with a plurality of openings through which extend the push button handles 12 for operating the breaker mechanisms. The box cover 2 is provided with a generally central opening which closely receives a slightly raised portion 13 in the cover 4 so that the operating push button handles 12 extend to the box exterior. The hinged mounting of the metal cover 4 permits the circuit breaker to be swung to the exterior of the box to facilitate pulling in and connecting of the circuit wires. To then secure the circuit breaker within the box interior it is swung back to its interior position with the bolt 9 re-

ceived within the slot 31 whereupon tightening of the bolt 9 will secure the circuit breaker in position.

The individual circuit breaker mechanisms 5 comprise a movable contact bar 14 carrying a contact tip 15 adapted to engage with a common stationary contact 16 which is rigidly secured to the base by means of a bolt 17. The free end of the contact bar 14 is normally latched in the 10 position shown at the bottom of Figure 2 by the bimetallic current responsive member 18. The bimetallic strip 18 is rigidly welded or otherwise secured to an arm 19 centrally punched or otherwise spaced from the main part of a connector 21 which is rigidly secured to the base by means of rivet 22. The side arms thus formed at the end of the connector 21 are bent over as 15 at 23 and within the space formed between the connector 21, the bent-over portions 23 and the 20 arm 19 is disposed a block 24 through which is threaded a stud 25 bearing against the free end of arm 19 and thus serving as an adjusting or calibrating means for the bimetallic strip. Within the rivet 22 is threaded a stud 26 forming the 25 terminal for the breaker. A flexible lead 27 connects the free end of bimetallic strip 18 with the contact bar 14 adjacent to a pivot point thereof to be hereinafter described. The portion of the bar 14 between the lead 27 and the 30 bimetal 18 is provided with holes or otherwise reduced in cross-section to increase its resistance and lessen the current passing directly from the bimetal to the bar through their latching engagement.

35 A compression spring 28 is provided between the base 3 and the contact bar 14 and acts to bias the bar away from the main body of the base. This spring is located closer to the contact tip 15 than to the latching end of the bar to provide a high contact pressure without unduly increasing the pressure between the bar and the bimetallic latching member.

For operating the contact bar 14 there is provided a generally U-shaped member 29 having legs of different lengths. The longer leg of the member 29 is provided with a slot 31 in which the contact bar is disposed. The upper portion of the bar within this slot is provided with a notch 32 engaging the end of the slot and serving 40 to restrain the bar from longitudinal movement as well as to provide a pivot point for movement of the bar to automatically trip and reset positions. The short leg of the U-shaped member is also slotted to receive the contact bar in over-load position as more particularly shown in 45 Figure 3.

The base 3 is provided with a plurality of up-standing walls 33 provided with slots receiving the bar 14 and with suitable projections for 50 holding and guiding the member 29 in its reciprocal movement.

In front of the operating member 29 is provided an L-shaped push button handle 12 having its leg extending through the cover 4. The base of the handle 12 is provided with a groove 55 34 mounted over a projection 35 on the closed end of the member 29. A small compression spring 36 is disposed within the handle base and bears against the under side of cover 4 in 60 position to normally maintain the upper side of the base a definite distance from the cover. The ends of the base of the L are provided with smooth curves to facilitate rotation of the push button handle about an axis at right angles 65 to its direction of straight line motion. The leg 70 75

and the adjacent curved portion of the L-shaped handle are of a size to fit snugly within the opening in the cover 4. The remaining portion of the base as at 37 is enlarged and in the rotated position of the handle forms flanges bearing 75 against the edges of the opening. A colored ring 38 may be placed on the outwardly projecting leg of the handle for a purpose to be hereinafter described.

The operation of this single circuit breaker 10 mechanism will now be described in detail.

The mechanism shown at the bottom of Figure 2 is in the normal closed operating position. In the circuit breaker at the top of Figure 2 the handle 12 has been rotated 90 degrees so 15 that the end of the base of the handle now bears upon the closed end of the member 29 with the enlarged portion 37 forced against the under side of cover 4 by spring 28. This in effect forms a simple toggle and the parts are maintained in 20 this position. As the length of the base of the handle from enlargement of portion 37 to the end is greater than the distance between member 29 and cover 4 in the normal operating position, the member 29 has been moved toward the 25 base moving the contact bar 14 by engagement of the end of slot 31 with notch 32 in the bar. In this movement the bar pivots about its engagement with the bimetallic member 18 and assumes the position shown in the upper circuit breaker in Figure 2 which is the manual 30 "off" position. In again closing the circuit 35 through the breaker it is only necessary to flip the handle back 90° to the position shown in the lower circuit breaker in Figure 2 whereupon the contact bar 14 is moved upwardly to the position therein shown under action of the compression spring 28. When an over-load is passed through the circuit breaker it becomes heated and is deflected away from the contact bar 14 40 thus releasing the end thereof and permitting this end to move away from the main body of the base 3. This movement of the contact bar 14 is caused by the compression spring 28 and the bar 14 moves about the engagement of the 45 notch 32 with the top of the slot 31 into the position shown in Figure 3. The upward movement of the contact bar is restrained only by its engagement with member 29 which presses against the base of the push button handle 12. 50 As the spring 36 is relatively weak as compared with the spring 28, the base of the handle will be moved against the under side of the cover 4 and the over-load tripped condition of the breaker will be indicated by the extended position of the arm of the handle which brings the colored ring 38 into view above the cover. 55 To reset the breaker mechanism it is necessary only to press inwardly upon the push button handle 12. In the extreme inward movement 60 of the handle, the parts assume the reset position shown in Figure 4 with the end of the contact bar again in a position to have its upward movement restrained by the bimetallic member 18 and with the contact tip separated from the 65 stationary contact 16. When the handle is released it will be moved outwardly to the position of the lower breaker in Figure 1 under action of spring 28 and the movable contact 15 will be engaged with the stationary contact. 70 By this method of resetting it is obviously impossible to prevent the automatic tripping of the breaker by holding the operating handle as the contacts are not engaged to close the circuit until the operating handle moves to its normal 75

operating position. If the push button handle is pushed inwardly and held there the contacts simply remain separated as shown in Figure 4. If the operating handle should be held in its 5 nonindicating position as shown in the lower portion of Figure 2 the contacts will separate to the same extent although the now free end of the contact bar will not move to its full upward position until the handle is released. However, 10 the contact carrying end of the bar will still move against the main body of the base and separate the contacts.

The connection of the flexible lead 27 to an intermediate point on the bar 14 serves two 15 functions as it not only lessens the movement of the lead, but also by bypassing a length of the bar places its resistance in the circuit through the latching engagement. This resistance may be increased in any desired manner, one simple 20 means being, as shown, the reduction in the cross section of the bar between its latching end and the point of connection of the flexible lead.

Guides or stops 10 and 20 are provided at the ends of the bar 14. These limit and guide 25 the longitudinal movement of the bar. The limiting stop 10 also provides a positive pivot point for the bar in its movement to reset position. The stop 20 also prevents the bar moving with the bimetal where there is play at the notch 32.

30 In the multi-circuit circuit breaker according to the present invention, a plurality of circuit breaker mechanisms are mounted upon base 3. In the specific example herein disclosed the base is provided with a generally central dividing wall 39 which divides the mechanism into two duplicate and electrically separate parts each of which may be regarded as a multi-circuit circuit breaker. In the specific example herein shown and described four individual circuit breaker mechanisms are provided. The 35 stationary contacts are here in the form of a single large stationary contact 16 with which the four movable contacts 15 cooperate. It is, of course, within the spirit of the present invention that in a multi-circuit circuit breaker a plurality of contacts electrically joined together could be used. However, it is preferred to use contacts 40 having a common mechanical mounting and for this purpose the single contact plate shown as at 16 in the drawings is preferred. This latter construction not only results in a considerable saving of parts and mounting economies but also due to its large mass considerably limits the heating due to any one contact as the 45 heat generated will be distributed throughout the large mass of the contact and will have a greater surface from which to be dissipated.

50 Describing now the multi-circuit circuit breaker shown at one side of the dividing wall 39, there is provided a central wall 41 having a cutout portion 42 in which is maintained the contact 16. The bolt 17 projects upwardly through the central portion of the wall 41 and rigidly secures the contact to the base. The 55 opening through which the bolt 17 projects may then be waxed to provide insulation. Between the contact 16 and the supporting portion of the wall 41 is disposed an insulating strip 43 having cutout portions through which the movable contacts project to engage the contact 16. The insulating strip 43 projects beyond the contact 16 on both sides of the wall 41 to the member 29 and in combination with the walls of the base forms an arc chamber. This arrangement permits the discharge of gas from the rup-

turing of a single breaker into the space occupied by the multiple group of breakers thus rendering less necessary any important discharge vent to the outer air. The central wall 41 may be integral with certain of the walls 33 and in this 5 construction the walls 33 may be considered to form projections upon the side walls of the base and the wall 41 rather than as unitary walls slotted to receive the member 14. The ends of the breaker are provided with fibre shields 45 10 extending between the base 3 and the cover 4 and sealable therewith by rivet 5.

In the multi-circuit circuit breaker as hereinbefore described, it is provided that one breaker mechanism may be a main breaker and feed 15 from the line to the stationary contact 16. The three other circuit breaker mechanisms of each breaker will then constitute branch circuit breakers leading from the contact 16 to the individual branch circuits. The contact 16 here 20 forms the load side of the main breaker and the line side of the branch breakers. The circuit breaker is sealable and it is impossible to place a short directly on the load side of the main breaker or the line side of the branch breakers 25 but any short must occur on the load side of the branch breakers and there will always be two circuit breaker mechanisms in series with any short which may occur. This is a desirable safety factor and it is in conformance with many 30 safety requirements which require main as well as branch circuit protection.

A slightly modified form of construction is shown in Figure 6 wherein a connector 46 extends through the side wall of the breaker and is 35 rigidly secured to the contact 16 by bolt 17. This connector 46 may serve as a tap on the load side of the main breaker if the feeding is as heretofore described. However, it may sometimes be desired to omit what has been termed 40 the main breaker and feed directly through the four individual breakers to the branch circuits. The connector 46 would then serve as the incoming main connected directly to the contact 16 and the branch circuit breakers would then lead 45 directly from the main to the branch circuits. In the case where the connector 46 is a tap a safety factor is lost as it is now possible to place a short on the load side of the main breaker where only one circuit breaker mechanism will 50 be in series with the short, also where the connector 46 is used as a line lead-in the safety of the main breaker is lost.

Also shown in Figure 6 is a magnetic plate 47 placed beneath the contact 16. While this plate 55 may be of unitary construction it is preferred to form it as here shown of a plurality of thin laminated magnetic sheets, having no insulation other than incidental air space and incidental surface oxide. As here shown the fibre plate 43 insulates the magnetic plate 47 from the contact 16. In some instances it might be desirable to mount the plate 47 directly against the contact 16 in which case the fibre sheet will be omitted. The plate 47 is cut out to provide passage for the movable contacts and takes the double H shape shown in Figure 7. Further arc suppressing means are embodied by the insulating plates 48 disposed closely adjacent to the path of movement of the movable contacts 60 and on either side thereof. These insulating plates serve to confine and cool the arc drawn between the separated contacts. While the circuit breaker shown in Figure 6 embodies both the magnetic and parallel plate arc suppressing 70 75

means it is readily understood that either or both of them may be omitted from the circuit breaker assembly.

While certain preferred embodiments of the invention have been specifically disclosed, it is understood that the invention is not limited thereto as many variations will be readily apparent to those skilled in the art and the invention is to be given its broadest possible interpretation within the terms of the following claims:

What is claimed is:

1. In a unitary, automatic multi-circuit circuit breaker, a base, a plurality of individual automatically and manually operable electric circuit breaker mechanisms supported by said base, means cooperating with said base to form an enclosure for said mechanisms sealed from outside access, said mechanisms having electrically common parts at the same electrical potential and connected to feed from said common parts through the individual mechanisms to individual branch circuits.
2. In a unitary, automatic multi-circuit circuit breaker, a base, a plurality of individual automatically and manually operable electric circuit breaker mechanisms supported by said base, means cooperating with said base to form an enclosure sealed from outside access, said mechanisms having electrically common parts within the enclosure at the same electrical potential, terminals at the exterior of the enclosure, said mechanisms being connected between said electrically common parts and said exterior terminals to individually feed thereto.
3. In a unitary automatic multi-circuit circuit breaker, a base, a plurality of individual circuit breaker mechanisms supported by said base, individual movable contacts actuated by said mechanisms, the cooperating contacts being at least electrically common and supported within the circuit breaker enclosure.
4. In a unitary automatic multi-circuit circuit breaker, a base, a plurality of individual circuit breaker mechanisms supported by said base, individual movable contacts actuated by said mechanisms and a common stationary contact supporting a plurality of contact surfaces in position to be engaged by said movable contacts.
5. In a unitary automatic multi-circuit circuit breaker, a base, a plurality of individual circuit breaker mechanisms supported by said base within a sealable enclosure, individual movable contacts actuated by said mechanisms, at least some of said contacts being load contacts for their corresponding breaker mechanisms, and cooperating, stationary line contacts for at least said corresponding breaker mechanisms which are at least electrically common and supported within the sealable enclosure.
6. In an automatic multi-circuit circuit breaker, a base, a main circuit breaker mechanism supported by said base, a plurality of branch circuit breaker mechanisms supported by said base, each of said mechanisms including cooperating contacts automatically separable in response to a current overload, the load contact of the main breaker and the line contacts of the branch breakers being at least electrically common and sealable within the circuit breaker interior.
7. In an automatic multi-circuit circuit breaker, a base, a main circuit breaker mechanism supported by said base, a plurality of branch cir-

cuit breaker mechanisms supported by said base, each of said mechanisms including a contact automatically movable in response to a current overload, and a common stationary contact sealable within the circuit breaker interior and constituting the load contact of the main breaker and the line contacts of the branch breakers.

8. In an automatic multi-circuit circuit breaker, a base, a main circuit breaker mechanism supported by said base, a plurality of branch circuit breaker mechanisms supported by said base, each of said mechanisms including a contact automatically movable in response to a current overload, a common stationary contact within the circuit breaker interior and constituting the load contact of the main breaker and the line contacts of the branch breakers and a connector secured to said stationary contact and extending to the exterior of the breaker.

9. In a unitary automatic multi-circuit circuit breaker, an enclosure sealed from outside access, a plurality of movable contacts in said enclosure, separate operating means for said movable contacts including manually operable handles projecting from said enclosure and current responsive elements for automatically releasing said movable contacts on overload, and at least electrically common stationary contacts within said enclosure in position to be engaged by said movable contacts.

10. In a unitary automatic multi-circuit circuit breaker, an enclosure, a plurality of movable contacts in said enclosure, separate operating means for said movable contacts including manually operable handles projecting from said enclosure and current responsive elements for automatically releasing said movable contacts on overload, and a common stationary contact element within said enclosure carrying a plurality of contact surfaces in position to be engaged by said movable contacts.

11. In an automatic multi-circuit circuit breaker, a base, a stationary contact element spaced from the main body of the base and carrying a plurality of contact surfaces, a plurality of movable contact bars having contacts thereon disposed between said contact surfaces and the main body of the base, the ends of the bars remote from said contacts being normally restrained, and individual members about which said bars are adapted to pivot when released, the ends of the bars supporting the contacts moving toward the main body of the base to open the circuit therethrough.

12. In an automatic multi-circuit circuit breaker, a base, parallel walls on said base, slots in said walls for the reception of movable contact bars, extensions on said walls cooperating with said walls to guide manipulable members engaging said bars, a stationary contact element carrying a plurality of contact surfaces supported between a central pair of said walls, and an insulating sheet beneath said contact element having openings receiving the contact tips on said bars, said sheet cooperating with said walls on the base to form an arc chamber.

13. In an automatic multi-circuit circuit breaker, a base, a common stationary contact element carrying a plurality of contact surfaces, a plurality of movable contacts cooperating therewith, individual circuit breaker mechanisms for said movable contacts, said mechanisms being individually manually operable to move their respective contacts and individually automatically operable in response to overload to move their respective contacts, and arc suppressor surfaces

- extending on either side of and closely adjacent to the path of movement of said contacts.
14. In an automatic multi-circuit circuit breaker, a base, a common stationary contact element carrying a plurality of contact surfaces, a plurality of movable contacts cooperating therewith, individual circuit breaker mechanisms for said movable contacts, said mechanisms being individually manually operable to move their respective contacts and individually automatically operable in response to overload to move their respective contacts, and insulating suppressor plates extending from said stationary contact element in the direction of movement of said movable contacts, said plates being located on either side of and closely adjacent to their path of movement.
15. In an automatic multi-circuit circuit breaker, a base, a plurality of circuit breaker mechanisms on said base, a plurality of manually operable handles for said mechanisms, said mechanisms being individually manually operable to separate their contacts and individually automatically operable to separate their contacts in response to an overload and a metallic cover for said circuit breaker having a plurality of openings through which said handles project, said cover being sealably attached to said base and hingedly attached to an enclosing box, said cover forming part of the cover for said box, and supplemental cover means for closing said box.
16. In an automatic multi-circuit circuit breaker, a base, a plurality of individual circuit breaker mechanisms supported by said base, individual movable contacts actuated by said mechanisms, the cooperating contacts being at least electrically common and supported within the circuit breaker enclosure, the arcs formed between cooperating contacts being interrupted in a common chamber.
17. In an automatic multi-circuit circuit breaker, a base, a plurality of individual circuit breaker mechanisms supported by said base, individual movable contacts actuated by said mechanisms, a common stationary contact plate supporting a plurality of contact surfaces in position to be engaged by said movable contacts, and a common chamber for the interruption of arcs formed by the opening movement of said movable contacts.
18. In a unitary, automatic multi-circuit circuit breaker, a sealable enclosure, a plurality of individual circuit breaker mechanisms within said enclosure, a common terminal for said mechanisms sealable within the enclosure from outside access, and individual opposite terminals for said mechanisms accessibly mounted at the exterior of the enclosure.
19. In an automatic multi-circuit circuit breaker, an enclosure, electrically connected stationary contacts disposed intermediate the ends of said enclosure, and a plurality of individual circuit breaker mechanisms including automatically and manually movable contacts cooperating with said stationary contacts, said mechanisms being disposed between said stationary contacts and the opposite ends of the enclosure.
20. In an automatic multi-circuit circuit breaker, a sealable enclosure, electrically connected stationary contacts disposed intermediate the ends of said enclosure, a plurality of individual circuit breaker mechanisms including automatically and manually movable contacts cooperating with said stationary contacts, at least one of said mechanisms being disposed between

said stationary contacts and each end of said enclosure.

21. In an automatic multi-circuit circuit breaker, a base, a connected cluster of stationary contacts intermediate the ends of the base, a plurality of elongated floating members carrying contact surfaces at one end cooperating with said contacts, the opposite ends of said members extending in opposite directions toward the ends of the base, individual current responsive latching means for said members, and individual biasing means for moving said members when released by said latching means to move their respective contact surfaces to a disengaged position.

22. In an automatic multi-circuit circuit breaker, a base, a plurality of electrically connected, closely adjacent stationary contacts disposed intermediate the ends of the base, a plurality of movable contact members carrying contact surfaces at one end adapted to cooperate with said contacts, the opposite ends of said members extending in opposite directions toward the ends of the base, and individual automatic circuit breaker mechanisms for moving said members in response to a current overload to cause relative movement between said contact surfaces and contacts.

23. In an automatic multi-circuit circuit breaker, an enclosure, a plurality of at least electrically common stationary contact surfaces within said enclosure, a plurality of elongated, floating members within said enclosure carrying contact surfaces at one end cooperating with said stationary contact surfaces, individual current responsive latching means for the opposite ends of said members, individual means biasing said members against said contacts and latching means, each of said members moving its contact surface to a disengaged position under the action of its biasing means when released by said latching means.

24. In an automatic multi-circuit circuit breaker, an enclosure, an at least electrically connected cluster of stationary contact surfaces disposed intermediate the ends of said enclosure, at least one elongated, floating member extending from the cluster toward each end of the enclosure, the ends of said members adjacent said cluster carrying contact surfaces cooperating with said stationary contact surfaces, individual current responsive latching means for the opposite ends of said members, individual means biasing said members against said stationary contact surfaces and latching means, and individual pivotal axes for said members interjacent the biasing means and contact surfaces about which the members rotate when released by said latching means to separate the cooperating contact surfaces.

25. In an automatic multi-circuit circuit breaker, a pair of electrically connected, closely adjacent stationary contacts, substantially aligned movable contact members carrying contact surfaces cooperating with said contacts, individual circuit breaker mechanisms for said members, a magnetic surface extending at one side of the path of movement of both said contact surfaces, a magnetic surface extending at the other side of the path of movement of both said contact surfaces, and a magnetic portion interconnecting said magnetic surfaces.

26. In an automatic multi-circuit circuit breaker, a contact element carrying a plurality of contact surfaces, a plurality of movable con-

- tacts cooperating with said surfaces, individual circuit breaker mechanisms for said movable contacts, and a common magnetic member cooperating with said contacts to assist in quenching an arc drawn therebetween.
27. In an automatic multi-circuit circuit breaker, a contact element carrying a plurality of contact surfaces, a plurality of movable contacts cooperating with said surfaces, individual circuit breaker mechanisms for said movable contacts, a common magnetic member cooperating with said contacts to assist in quenching an arc drawn therebetween, said member having portions disposed on either sides of the path of the movable contacts and a portion connecting said first mentioned portions.
28. In an automatic multi-circuit circuit breaker, a pair of electrically connected, closely adjacent, stationary contacts, substantially aligned movable members carrying contact surfaces cooperating with said contacts, individual circuit breaker mechanisms for said members, an arc suppressor surface extending at one side of the path of movement of both said contact surfaces, and an arc suppressor surface extending at the other side of the path of movement of both said contact surfaces.
29. In an automatic multi-circuit circuit breaker, a pair of electrically connected, closely adjacent stationary contact surfaces, substantially aligned movable members carrying contact surfaces cooperating with said stationary contact surfaces, individual circuit breaker mechanisms for said members, surfaces extending on both sides of the path of movement of both said contact surfaces, and liners for said last mentioned surfaces formed of a material to facilitate the arc suppressing function of the surfaces.
30. In an automatic multi-circuit circuit breaker, a base, a plurality of electrically connected, closely adjacent, relatively stationary contacts supported on the base, a plurality of movable contact members carrying contact surfaces cooperating with said contacts, a plurality of individual circuit breaker mechanisms for said members supported on said base, and an arc chamber on said base common to said contacts.
31. In an automatic multi-circuit circuit breaker, an arc chamber, a plurality of electrically connected, closely adjacent contacts disposed in said chamber, a plurality of movable members carrying contact surfaces within said chamber cooperating with said contacts, and a plurality of individual automatic electric circuit breaker mechanisms for moving said members, said chamber facilitating the interruption of arcs drawn between cooperating contacts and contact surfaces.
32. In an automatic multi-circuit circuit breaker, a base, a chamber for arc gases substantially centrally of said base, electrically connected stationary contacts in said chamber, a plurality of movable members carrying contact surfaces within said chamber cooperating with said contacts, and a plurality of individual automatically and manually actuatable circuit breaker mechanisms for moving said members, at least one set of said members and mechanisms being located between said chamber and each end of the base.
33. In an automatic multi-circuit circuit breaker, a base, a cover sealably attachable to said base to form a unitary enclosure, electrically connected stationary contact surfaces mounted within the enclosure, a plurality of individual movable contacts cooperating with said contact surfaces, and individual automatically and manually actuatable circuit breaker mechanisms within the enclosure for operating said movable contacts, the manual means for actuating said mechanism projecting through the cover to the exterior of the enclosure.
34. In an automatic multi-circuit circuit breaker, a base, a cover sealably attachable to said base to form a unitary enclosure, a stationary contact plate mounted on said base within the enclosure, a plurality of individual movable contacts cooperating with said contact plate, and individual automatically and manually actuatable circuit breaker mechanisms within the enclosure for operating said movable contacts, the manual means for actuating said mechanism projecting through the cover to the exterior of the enclosure.
35. In an automatic multi-circuit circuit breaker, a base, a cover sealably attachable to said base to form a unitary enclosure, a contact plate mounted on said base intermediate the ends thereof, a plurality of individual movable contacts cooperating with said contact plate, individual automatically and manually actuatable circuit breaker mechanisms within the enclosure for operating said movable contacts, at least one of said mechanisms being located between the contact plate and each end of the enclosure.
36. An electric circuit breaker assemblage comprising a unitary base having a generally centrally disposed dividing wall extending from end to end of the base and dividing it into two sections of opposite polarity, a plurality of stationary contact surfaces disposed intermediate the ends of the base on each side of said dividing wall, the contact surfaces on the same side of the wall being electrically connected and insulated from the contact surfaces at the opposite side of the wall, a plurality of movable contacts cooperating with said stationary contact surfaces, and individual automatically and manually actuatable circuit breaker mechanisms for moving said movable contacts, and cover means sealably attached to said base to enclose said contact surfaces, contacts and mechanisms.
37. An electric circuit breaker assemblage comprising a unitary base having a plurality of deep compartments therein, a generally central dividing wall extending substantially from end to end of the base and dividing it into two sections of opposite polarity, a group of electrically connected stationary contact surfaces disposed intermediate the ends of the base on each side of said dividing walls, said groups being of different polarity and electrically insulated from each other, a plurality of movable members carrying contact surfaces adapted to cooperate with said stationary contact surfaces, and a plurality of individual automatically and manually actuatable circuit breaker mechanisms for moving said members, at least one set of said members and mechanisms, on each side of the dividing wall, being located between the stationary contacts and each end of the base.
38. An electric circuit breaker assemblage comprising a unitary base having a plurality of deep compartments therein, a generally central dividing wall extending substantially from end to end of the base and dividing it into two sections of opposite polarity, a group of electrically connected stationary contact surfaces disposed intermediate the ends of the base on each side of said dividing wall, said groups being of different polar-

- ity and electrically insulated from each other, a plurality of movable members carrying contact surfaces adapted to cooperate with said stationary contact surfaces, and a plurality of individual 5 automatically and manually actuatable circuit breaker mechanisms for moving said members, at least one set of said members and mechanisms, on each side of the dividing wall, being located between the stationary contacts and each end of the base, and a cover for said base sealably attachable thereto to prevent unauthorized access, said mechanisms including manual operating handles projecting through the cover to a readily accessible position.
39. In an automatic multi-circuit circuit breaker, a unitary base having an elongated compartment in substantial communication from end to end of the base, electrically connected stationary contact surfaces in said compartment and intermediate the ends of the base, said surfaces being adjacent and spaced longitudinally of the base, substantially aligned movable members carrying contacts cooperating with said stationary contact surfaces, individual automatically and manually actuatable circuit breaker mechanisms for moving said members, said members and mechanisms being disposed between said stationary contact surfaces and the opposite ends of the base, and cover means sealably enclosing said 30 chamber.
40. In an automatic multi-circuit circuit breaker, a unitary base having an elongated compartment in substantial communication from end to end of the base, electrically connected stationary contact surfaces in said compartment and intermediate the ends of the base, said surfaces being adjacent and spaced longitudinally of the base, substantially aligned movable members carrying contacts cooperating with said stationary contact surfaces, individual automatically and manually actuatable circuit breaker mechanisms for moving said members, said members and mechanisms being disposed between said stationary contact surfaces and the opposite ends of the base, and spaced walls slotted to provide passage 45 for said members and serving to form an intermediate chamber portion about said contact surfaces and contacts.
41. In an automatic multi-circuit circuit breaker, a unitary base having an elongated compartment in substantial communication from end to end of the base, electrically connected stationary contact surfaces in said compartment and intermediate the ends of the base, said surfaces being adjacent and spaced longitudinally of the base, substantially aligned movable members carrying contacts cooperating with said stationary contact surfaces, individual automatically and manually actuatable circuit breaker mechanisms for moving said members, said members and mechanisms being disposed between said stationary contact surfaces and the opposite ends of the base, and insulating formations serving to substantially isolate the portion of said chamber containing the contact surfaces and contacts from the portions of the chamber containing said mechanisms.
42. In an automatic multi-circuit circuit breaker, a unitary base having an elongated compartment in substantial communication from end to end of the base, electrically connected stationary contact surfaces in said compartment and
- and intermediate the ends of the base, said surfaces being adjacent and spaced longitudinally of the base, substantially aligned movable members carrying contacts cooperating with said stationary contact surfaces, individual automatically and manually actuatable circuit breaker mechanisms for moving said members, said members and mechanisms being disposed between said stationary contact surfaces and the opposite ends of the base, insulating formations serving to substantially isolate the portion of said chamber containing the contact surfaces and contacts from the portions of the chamber containing said mechanisms, and at least partial barrier means in said intermediate chamber portion between the cooperating pairs of stationary contact surfaces and movable contacts.
43. In an automatic electric circuit breaker a base having at least one cup-shaped compartment therein an end wall of said compartment being shorter than the side walls thereof and having a substantial thickness to form an exterior ledge a connector mounted on said ledge to form a terminal for the circuit breaker and leading into the interior of the compartment, electric circuit breaker mechanism within said compartment and including separable contacts and automatic and manual means for separating said contacts, and an insulating barrier sheet spanning said side walls adjacent to said end wall and directed toward said connector to close the end opening into said compartment in front of the ledge.
44. In an automatic electric circuit breaker, a base having at least one cup-shaped compartment therein, an end wall of said compartment being shorter than the side walls thereof and having a substantial thickness to form an exterior ledge, a connector mounted on said ledge to form a terminal for the circuit breaker and leading into the interior of the compartment, electric circuit breaker mechanism within said compartment and including separable contacts and automatic and manual means for separating said contacts, and an insulating barrier sheet spanning said side walls adjacent to said end wall and directed toward said connector to close the end opening into said compartment in front of the ledge, said barrier sheet being interlocked with the side walls of the compartment so that movement thereof is prevented except forwardly of the base.
45. In an automatic electric circuit breaker, a base having at least one cup-shaped compartment therein, an end wall of said compartment being shorter than the side walls thereof and having a substantial thickness to form an exterior ledge, a connector mounted on said ledge to form a terminal for the circuit breaker and leading into the interior of the compartment, electric circuit breaker mechanism within said compartment and including separable contacts and automatic and manual means for separating said contacts, an insulating barrier sheet spanning said side walls adjacent to said end wall and directed toward said connector to close the end opening into said compartment in front of the ledge, said barrier sheet being interlocked with the side walls of the compartment so that movement thereof is prevented except forwardly of the base, and a cover sealably attached to the front of said base and preventing removal of said barrier sheet.

JOHN G. JACKSON.
